Attorney

UNITED STATES PATENT OFFICE.

STEPHEN STEPANIAN, OF COLUMBUS, OHIO.

WRENCH.

1,321,776.

Specification of Letters Patent. Patented Nov. 11, 1919.

Application filed May 29, 1918. Serial No. 237,289.

To all whom it may concern:

Be it known that I, STEPHEN STEPANIAN, a citizen of the United States, residing at Columbus, in the county of Franklin and State 5 of Ohio, have invented certain new and useful Improvements in Wrenches, of which the following is a specification.

This invention relates to wrenches, and has for its primary object to provide an improved and efficient form of tool possessing novel features of construction which render the same particularly useful in effecting the adjustment of grease cups, pet cocks and other similar objects.

Another object of the invention resides in a wrench of this character wherein is provided an integral metallic body, formed to include an elongated handle and a socketed head portion, the latter comprising a plurality of tapering, separated finger elements which are formed internally to provide a substantially conical concavity, the walls of the latter being stepped to produce a plurality of sockets of varying diameters, whereby 25 the wrench will be capable of firmly gripping for rotation various sized threaded bodies, and the openings formed between the finger elements being capable of receiving the handle members of the type found upon 30 grease cups of certain formation, or upon pet cocks or the like, whereby the latter handles may be conveniently operated and their adjustments effected through the use of my improved wrench.

The invention consists in the novel features of construction, combination of elements, and arrangement of parts hereinabove fully described, illustrated in the accompanying drawing, and particularly defined in the claims hereunto appended.

In the drawing:

Figure 1 is a side elevation of the wrench comprising the preferred form of the invention,

Fig. 2 is an enlarged vertical sectional view taken through the socketed head member thereof, and

Fig. 3 is a plan view of said head member.

Similar characters of reference denote like and corresponding parts throughout the several views of the drawing.

Referring more particularly to the manner of constructing the preferred form of my invention, I employ a wrench 1, which in this instance consists of an integral me-

tallic body, formed to include an elongated T shaped handle 2, and an integral, flaring head member 3. This head member consists of a plurality of tapering, separated finger elements 4, which provide therebetween a plurality of substantially V shaped openings 5.

The inner faces of the elements 4 are upwardly tapered to provide a substantially conical cap receiving socket 6, which socket in this instance is stepped so that the socket is considerably varied at different positions throughout its length in diameter, and the faces of said finger elements forming the 70 socket 6 are formed with serrated teeth 7, the latter enabling the wrench to readily grip for rotation in a positive and secure manner the caps 8 of grease cups 9.

By virtue of this construction it is not necessary to taper the walls of the socket 6 to such extent as to interfere with the grip they afford upon the caps 8. Since if the taper of said socket were continuous as shown in my co-pending application, bearing Serial Number 204,161 filed November 27, 1917, the area of gripping relation existing between the walls of the socket 6 and the cap 8 is comparatively small, and oftentimes this permits the wrench to slip when being 85 rotated. However, by stepping the socket, the gripping area of the latter is considerably enlarged, so that the said caps will be firmly clutched for uniform rotation therewith. In the event of a grease cup being 90 provided with a cap formed with a handle, the latter may be rotated by inserting the wrench in such manner that the handle will be caught between the finger elements by being positioned in certain of the openings 95 5, whereby upon revolving the wrench, said handle may be effectively rotated to assume its several operating positions. In the same manner the handle of a pet cock or the like may be received within one of the openings 100 5 so that the operation of the valve may be easily effected.

From the foregoing description, taken in connection with the accompanying drawing, it will be apparent that there is provided a 105 wrench of considerable utility, the same being particularly adapted to effect the adjustments of grease cups, small valves and other like parts usually mounted in relatively inaccessible positions upon motor vehicles, and through the use of the wrench these parts may be readily adjusted in a 110

convenient manner without soiling the operator's clothing, or causing him to assume awkward positions. Through the use of the stepped socket 6, the wrench is enabled to 5 rotate all the grease cup caps found upon motor vehicles of standard design, and this is accomplished without adjusting or altering the socket in any manner to comply with proportions of the grease cups. Furthermore, the taper of the walls forming 10 the socket 6 is relatively small, so that a clutching area of considerable extent is provided, which would not otherwise be afforded through the use of a continuous 15 taper.

I claim:

1. A wrench of the character described, comprising a socketed head portion formed of a plurality of finger elements spaced

from each other to present longitudinally 20 arranged openings therebetween, the inner surfaces of said fingers being formed to present steps of increasing size whose inner surfaces are inclined downwardly and outwardly and a plurality of longitudinally arranged gripping teeth defining the inner surfaces of said stepped fingers. 25

2. A wrench of the character described, comprising an integral metallic body formed to include an elongated handle and a 30 socketed head portion, said latter comprising a plurality of tapering finger elements spaced to provide substantially V shaped openings therebetween, and the inner faces of said finger elements being stepped to provide 35 sockets of varying diameters.

In testimony whereof I affix my signature.
STEPHEN STEPANIAN.
